REFRIGERATION

Walter Jones, Princeton, N. J., assignor to Carrier Corporation, Syracuse, N. Y., a corporation of Delaware

Application August 1, 1940, Serial No. 349,155

14 Claims.

(Cl. 62—2)

This invention relates to refrigeration, and more particularly to features of construction and methods of operation employed in connection with a centrifugal refrigeration compressor assembled in combination with an evaporator, a condenser and related auxiliary elements.

Important features of the invention reside in the arrangement of a condenser superposed in position above an evaporator; the discharge of compressed refrigerant vapor from the compressor into the condenser in an upwardly direction; the wetting of condenser surfaces to eliminate superheat from incoming vapor discharged into the condenser; the regulation of flow of cooling medium within the condenser to facilitate concentration of non-condensable gases at an upper level of the condenser; the concentration of non-condensable gases in a quiet zone in which a relatively small percentage of condenser tube surfaces are subjected to air or non-condensable gas film; the distribution of incoming refrigerant vapor over a tube bundle, and prevention of vibrational stress at the points of entrance of the vapor; the segregation of condenser areas by a baffle arrangement to protect the tube shell, increase the velocity of the vapors in their course through the shell and yet provide a relatively quiet zone to prevent diffusion of non-condensable gases collected therein; facilitating removal of condensed refrigerant from the condenser shell; supporting removable finned tubes in support sheets while enabling such tubes easily to be removed; indicating accumulations of non-condensable gases and providing for efficient purging or removal thereof under a manual or automatic control; and recovering refrigerant from a mixture of non-condensable gas and refrigerant for reuse in the refrigerant cycle.

These and other features will be apparent from the following detailed description of a typical form of the invention to be read in connection with the accompanying drawings, in which:

Fig. 1 shows diagrammatically applicant's general arrangement of compressor, evaporator and condenser.

Fig. 2 diagrammatically represents certain features of the condenser plus the method of indicating accumulations of non-condensable gases therein.

Fig. 3 diagrammatically shows a condenser similar to that of Fig. 2 in association with a purge recovery system and a modified arrangement for indicating accumulations of non-condensable gases; and

Fig. 4 illustrates applicant's method of sup-

porting finned tubing in a tube sheet positioned intermediate the ends thereof.

Considering the drawings, similar designations referring to similar parts, numeral 5 designates an assembly of apparatus including a centrifugal compressor 6 employing a suitable refrigerant such as carrene No. 2(CFCl₃), condenser 7 and evaporator or cooler 8, all said elements being suitably aligned and assembled upon a bed 9 having two longitudinal base portions 10 and 11. Longitudinal base portion 10 may be mounted upon two support points 12, one adjacent each end of the base portion, whereas section 11 may rest upon a single support point 13 positioned midway of the base portion, between points 12 of base portion 10. This three point support arrangement assures the alignment of elements 6, 7 and 8 regardless of slight irregularities in the surface on which bed 9 is supported.

The cooler 8 and condenser 7 are preferably of the shell and tube type. In the cooler, the brine or other fluid to be cooled, e. g. water, flows through tubes 14, while in the condenser the cooling water flows through tubes 15. The refrigerant cycle starting at evaporator or cooler 8 is as follows: The brine, or water to be cooled, flowing through the tubes is warmer than the refrigerant in the shell surrounding the tubes. As a result, the refrigerant is evaporated at a temperature corresponding to the pressure in the evaporator. The refrigerant, in resultant vaporous form, passes through eliminators 16 into the suction of the compressor 6. The compressor normally has a plurality of stages of compression, and the compressed gas discharged from the last stage enters the condenser at a point proximate the bottom of the condenser as shown. The refrigerant discharged by the compressor into the condenser, condenses on the outside of tubes 15 at a temperature corresponding to the condenser pressure, the heat of condensation being transferred to the condenser water. The liquefied refrigerant from the condenser drains down an inside conduit into an economizer, described in U. S. Patent No. 2,277,647. From the economizer, which may or may not be incorporated with applicant's structure, the refrigerant in liquid form is routed to

the cooler to complete the cycle.

The compressed refrigerant gas enters the condenser at point 17 near the bottom thereof, rushing upwardly. Perforated sheet 18 prevents too forcible impingement of this high velocity gas from the compressor against tubes 15, thereby

preventing vibrational stress at the points of entrance. The perforations permit some of the gas to contact the tubes situated proximate the point of entrance, unlike other baffling arrangements which might make this portion of the condenser surface comparatively useless. The cooling water is routed through tubes 15 in one or more passes, preferably flowing from top to bottom or from upper levels to lower levels. The result is that with applicant's bottom intake arrangement, the gas in contacting the upper tubes will be condensed; and this will result in a shower of liquid refrigerant over the lower tubes, effectively wetting the lower tubes, and this eliminates superheat from the entering gas before such gas contacts the tube cooling surfaces. Without such upwardly discharge of refrigerant and consequent showering of condensate, the rate of heat transfer from the gas to the cooling water inside the tubes would be much lower.

The refrigerant normally used in applicant's system when discharged into the condenser, is in the form of a dense gas of high molecular weight. Any non-condensable gases present in the condenser are less dense and of lower molecular weight. The admission of the gas into the condenser causes turbulence in the lower part of the condenser. With the arrangement of upwardly discharge of gas and downwardly flow of cooling water as shown in Fig. 1, which results in this turbulent condition, the lighter non-condensable gases rise to the top of the condenser. By arranging the cooling water inlet at the top condensation takes place to a greater degree than if warmer water were circulated at this point, and this thorough precipitation of refrigerant gas results in a concentration of non-condensables at the top of the condenser substantially free of refrigerant at the upper point of accumulation. Thus, air and water vapor (non-condensables) are collected in a relatively small space so that a small percentage only of tube surface is subjected to air (and other non-condensable gas) film, leaving a greater proportion of condenser tube portions free from such film which cuts down heat transfer efficiency.

Furthermore, by arranging for precipitation of refrigerant in a downward shower, the turbulence in the lower portion of the condenser which results therefrom is maintained vigorously to prevent air film from forming on such tubes; this film destruction or breaking up process being vigorous and continuous. Also, the condenser tubes, as is also the case with the evaporator tubes, are provided with extended surfaces or fins. Since these fins produce in the aggregate a greater amount of surface than plain tubes, the air film where it does affect some of the tubes is much thinner than if plain tubes were employed with the result that the reduction in heat transfer efficiency is held to a minimum.

The use of fin surfaces of the type, for example, shown in Fig. 4, provides a large amount of surfaces, enabling the use of a much smaller shell. Consequently, much greater velocities over the surfaces in the smaller space are obtained and this further promotes turbulence and heat exchange compared to that obtainable with gas moving at a slow rate. The fast moving gas provides another advantage in that it serves to reduce the thickness of such air film as may be formed at tube surfaces to a minimum.

Baffle 19, as shown, is located within the tube bundle in the condenser. It is preferably made of non-ferrous material immune from attack by

water vapor in the presence of air at the upper part of the shell. The shell is usually made of ferrous material. Baffle 19 may extend for a considerable distance along the top of the shell to cover the area wherein non-condensables are collected and thereby protects the upper part of the shell from corrosion. By extending about two-thirds of the distance across the shell it serves to increase the velocity of the gas over a major part of the tube bundle by increasing the length of travel. This, as pointed out, is of major effectiveness in promoting great efficiency in heat exchange. Furthermore, the baffle provides a quiet zone thereabove wherein the non-condensables are collected. Turbulence and velocity are at a minimum in this zone, thereby facilitating concentration of the non-condensables, and conversely prevents diffusion of the non-condensables.

As is pointed out more clearly in Fig. 3, the condenser may be provided with an inclined element or plate 20 for draining condensed refrigerant to condenser discharge point 21. The condenser structure essentially consists of a shell 22, and includes tube sheets 23 and intermediate tube-supporting sheets 24. The tubes, at their ends, may be suitably enlarged or rolled into tube sheets 23 and may be supported at support sheets 24 by enlarging the fin tubing at their points of contact 25 with the support sheets. The result is that the finned surfaces at the points of contact with support sheets 24 are held in firm frictional engagement, not easily separated unless the tube is pushed through the support sheet with some force.

For removing the non-condensables from the top of the condenser, a purge-recovery arrangement is provided with an effective means for indicating the extent to which air and other non-condensables may be present. An indicator or gauge 26 is provided. It has two hands, one of which is preferably colored red to indicate the total pressure in the condenser and the other may be black or otherwise colored to indicate the refrigerant condensing temperature or partial pressure when air is present. The black hand responds to pressure of a refrigerant, the same as that used in the refrigeration cycle, contained in a thermal bulb 27 exposed to the condensing temperature. This bulb may be located in a compartment 28 at the point of evacuation as shown in Fig. 2, or may be positioned for immersion in the refrigerant normally flowing from the bottom of the condenser, as shown in Fig. 3. When air is present the total pressure will exceed the refrigerant partial pressure. The difference is air pressure and is in proportion to the amount of air and other non-condensables in the condenser. The bulb is connected by tube 29 to actuate the black hand whereas conduit 28, suitably connected to reflect the total pressure in the condenser is connected to the red hand. Conduit 31 desirably connected to the upper part of the condenser, through compartment 28 in the arrangement shown in Fig. 2, or directly as illustrated in Fig. 3, leads to an evacuating pump 32. This pump, suitably driven as by motor 33 may be controlled manually or automatically through control 34, which is operative responsive to a predetermined difference in pressures within the condenser. As a result, when evacuation is required, pump 32 will purge the system through conduit 31 and in doing so will pull a quantity of refrigerant with the non-condensables. The compressed gas and non-condensables will be discharged into air-cooled condenser 35, of suitable

design, the condensed refrigerant and the compressed non-condensables flowing into receiver 36. The non-condensables will be relieved from the receiver through valve 37. Float valve 38 will control the return of recovered refrigerant to the system through line 39.

Since many changes in construction, arrangement and operation may be made in the embodiments herein shown and described, without in any way departing from the scope of the invention, it is intended that the foregoing description is to be considered as illustrative and not in a limiting sense.

I claim:

1. A refrigerant condenser of the shell and tube type, comprising a tube bundle within the shell, means for admitting compressed refrigerant gas into the condenser at a point proximate the bottom of the condenser and in an upwardly direction whereby the gas is directed upwardly in contact with the tube bundle, and means for circulating a cooling fluid within the tubes of the bundle in such manner that the gas will be condensed in the upper part of the shell causing a shower of liquefied refrigerant to fall upon and wet tubes lower in the shell, the lower part of the shell comprising a turbulent zone in which a violent boiling action takes place, the evaporation of liquefied refrigerant falling on tubes adjacent said means for admitting refrigerant gas to the condenser causing elimination of superheat from refrigerant gas entering the condenser and contacting said tubes, and means providing a relatively quiet zone in the upper part of the shell to which non-condensable gases relatively lighter than the refrigerant rise.

2. A refrigerant condenser of the shell and tube type, comprising a tube bundle within the shell, an inlet for admitting refrigerant gas upwardly into the condenser to contact the outer surfaces of the tubes of the bundle, means for admitting cooling fluid into said tubes so that it flows downwardly within the bundle from an upper to a lower level in the condenser, said routing of refrigerant and cooling fluid causing a shower of condensed refrigerant to fall downwardly upon and wet the tubes adjacent the bottom of the condenser so that a turbulent zone is created in which superheat is removed from refrigerant gas admitted into the condenser in contact with said wetted tubes, means for relatively segregating a portion of the tube bundle at the upper part of the shell from the remainder of the tube bundle whereby a relatively quiet zone is maintained in the upper part of the condenser, the agitation in the turbulent zone causing a wiping away of air and other non-condensable gases from the tubes in said zone, said air and non-condensable gases rising into the quiet zone.

3. A refrigerant condenser according to claim 2, having fins on the outer tube surfaces, said fins providing a greater area of heat exchange surface whereby the air and non-condensable gases collected in the upper part of the shell will be spread over a greater area of surface and affect a relatively small proportion of the total heat exchange surface of the tubes in the bundle.

4. A refrigerant condenser according to claim 1, having means on the outer surfaces of tubes of the condenser for increasing the area of heat exchange surface in the condenser whereby the size of the shell may be decreased resulting in increased refrigerant gas velocity through the shell.

5. In a system of the character described a

condenser, refrigerant and non-condensable gases within said condenser, means for gauging the pressure within said condenser corresponding to the condensing temperature of the refrigerant within the condenser, means for gauging the total pressure within the condenser, and a device for indicating the difference between said pressures.

6. In a system of the character described a condenser, a thermal bulb within the condenser, means operative in response to the change in temperature of said thermal bulb for indicating a pressure corresponding to the condensing temperature of a refrigerant in the condenser, means for measuring the total pressure in the condenser, and means for evacuating non-condensable gases from the condenser when the difference in said pressures exceeds a predetermined number of pressure units.

7. In a system according to claim 6, a point of evacuation in the condenser, said thermal bulb being located proximate said point of evacuation, a refrigerant in said bulb, said refrigerant being substantially the same as that of the refrigerant in the condenser.

8. In a system according to claim 6, a control for actuating said evacuating means, said control being operative in response to a difference in said pressures in excess of said predetermined number of pressure units to cause said means automatically to operate until the total pressure in the condenser falls to a pressure substantially corresponding to the partial pressure exerted by the refrigerant in the condenser.

9. In a system according to claim 5, a thermal bulb in one portion of the condenser for exerting a pressure corresponding to the condensing temperature of a refrigerant in the condenser, a pressure conduit connecting said bulb to said indicating device, another conduit connected to another portion of the condenser and to said device for transmitting to the device the total pressure in the condenser, and a third conduit for withdrawing from the condenser non-condensable gases exerting a pressure in said second conduit.

10. In a system of the character described, a condenser, means in the bottom of the condenser for facilitating delivery of condensed refrigerant to a point of discharge, said means comprising an inclined bed running substantially the full length of the condenser, and an opening in the bottom of the condenser connecting with the inclined bed for discharging from the condenser refrigerant flowing from the inclined bed.

11. A refrigerant condenser comprising a shell, a plurality of tubes within said shell, said shell having an inlet opening for refrigerant gas located in the lower portion thereof and an outlet opening for condensed refrigerant located substantially at the bottom thereof, said inlet opening being arranged to deliver refrigerant gas passing therethrough in an upwardly direction within said shell and in contact with said tubes, a baffle within said shell, said shell having in the top thereof a relief outlet for non-condensable gases, said baffle being disposed between said inlet opening and said relief opening, and extending obliquely downwardly from the inner surface of the upper portion of said shell covering in excess of fifty percent of the diameter of the shell to form substantially a barrier between the area in the condenser adjacent the inlet where conditions of turbulence prevail and the area adjacent said relief opening wherein non-condensable gases are accumulated and where a relatively quiet condition exists.

12. A refrigerant condenser as defined in claim 11 in which said baffle extends substantially two-thirds of the distance across said shell to increase the velocity of refrigerant travel over a major part of said tubes.

13. A refrigerant condenser as defined in claim 11 in which said baffle constitutes an extension

of a protective lining provided for the inner surface of the upper part of said shell.

14. A refrigerant condenser as defined in claim 11 in which said baffle lies in a plane substantially perpendicular to the line of travel of refrigerant entering said shell through said inlet opening.

WALTER JONES.
